LAWNMOWER CHUTE

William R. Smith, McDonough, and Wallace A. Hanson,
Jr., Riverdale, Ga., assignors to McDonough Power
Equipment, Inc., McDonough, Ga.

Filed Mar. 29, 1968. Ser. No. 11,197

Term of patent 14 years

U.S. Cl. D40—1
Int. Cl. D8—01

FIG. 1

FIG. 2

FIG. 3

FIG. 4

FIG. 5

FIG. 6

FIGURE 1 is a right-hand, side elevational view of a lawn mower chute embodying our new design;

FIGURE 2 is a top plan view of the lawn mower chute;

FIGURE 3 is a front end view of the chute;

FIGURE 4 is a left-hand, side elevational view of the chute;

FIGURE 5 is a bottom plan view of the chute; and

FIGURE 6 is a rear end view of the chute.

The dominant features of the design reside in the full line portions of the drawing.

We claim:

The ornamental design for a lawn mower chute, substantially as shown and described.
